MOORING GEAR FOR FLYING BOATS

Henry Knowler, Isle-of-Wight, England, assignor to Saunders-Roe Limited, East Cowes, Isle-of-Wight, England

Application November 1, 1945, Serial No. 626,007
In Great Britain May 5, 1944

7 Claims. (Cl. 114—230)

1

The object of this invention is to facilitate picking up and releasing a mooring from a flying boat.

The existing method is for the flying boat to taxi up to a buoy, which is moored in open water, a member of the crew securing a line to the buoy from the flying boat.

It is difficult to carry out this operation from small flying boats, in which there is a pilot only and no crew, and with the advent of larger flying boats which, necessarily, have much more free-board, the height from the flying boat's mooring platform to the water is on the increase. This makes it more difficult to ensure that the craft will be secured with reasonable safety.

The invention provides, in a flying boat, the combination with a mooring hook fitted to the hull at or near the bow and serving to engage, by movement of the boat along the water, a mooring cable extending across the water at or near the surface thereof, of a catch for preventing disengagement of the cable from the hook, and manually operable release gear for releasing the catch and displacing the hook in relation to the hull so as to permit of disengagement of the cable from the hook by forward or aft movement of the boat in relation to the cable.

By the use of such a mooring gear the operation of securing the flying boat to the mooring cable is rendered simple, speedy and certain, and all danger to the personnel of the flying boat is eliminated. After engagement with the cable, the latter can be employed to tow the flying boat into a dock.

Preferably the hook is retractible into the hull of the flying boat so as to reduce drag during flight.

One form of mooring gear for a flying boat according to the invention will now be described in detail by way of example, with reference to the accompanying drawings, in which:

Fig. 1 is a vertical section through a portion of the keel of the boat, showing the mooring gear in elevation and in the operative position.

Fig. 2 is a section on the line II—II in Fig. 1, and

Figs. 3 to 6 are views similar to Fig. 1 showing successive positions taken up by the mooring gear on movement of the control shaft to release the cable and to retract the gear into the hull.

2

Like reference characters designate like parts throughout the figures.

An opening 10 is provided in the keel 11 of the flying boat near the bow and above this opening, inside the hull, is a casting 12 which is fixed to the upper surface of the keel 11 by any convenient means not shown.

In the casting 12 is fitted a transversely extending pivot pin 13 for a forwardly facing mooring hook 14. As shown in Fig. 2 there is a slight clearance between the hook 14 and casting 12 which allows the hook to slide sideways to a slight extent to enable side loads to be taken directly on the casting 12.

15 The position of the hook is determined by a link 15 pivoted at one end 16 to the hook 14 and at the other end on a pin 17 fitted to the lower end of a lever 18 fixed to a shaft 19. This shaft is rotatable by remote control from the cockpit through 20 the agency of any convenient mechanism such as an electric or hydraulic control gear or a system of cables and pulleys. Such a conventional means within the boat is shown diagrammatically in Fig. 1, 100 being a cable for imparting rotary movement to a pulley 101 fixed to shaft 19 when pulley 102 is turned by crank handle 103. In the operative extended position of the hook 14 shown in Fig. 1 a surface 20 of link 15 abuts against the surface 21 of lever 18, and link 15 and lever 18 25 constitute a rigid support for the hook. The surfaces 20 and 21 are shown in Fig. 3.

Pivoted at 22 to the hook 14 is a catch 23. The catch is normally held in the locking position shown in Fig. 1 by a spring 24 fixed to a plate 25 carrying arms 26, 27, which are respectively pivoted to the hook 14 at 28 and 29. A link 30 is pivoted at 31 to the catch 23 and is formed with a slot 32 engaging the pin 17 on the lever 18.

35 The hook serves to engage a mooring cable 33 stretched beneath the surface of the water as the flying boat taxis forward along the water. The cable 33 then moves in relation to the flying boat in the direction indicated by the arrow in 40 Fig. 1 and is able to push the catch 23 aside against the action of the spring 24 and so engage the hook 14 as shown in dotted lines in Fig. 1, the catch 23 then being returned by spring 24 into position to prevent disengagement of the cable 45 from the hook. The slot 32 in the link 30 permits

the above-described pivotal movement of catch 23 to allow the cable 33 to enter the hook.

When it is desired to cast off the release shaft 19 is rotated clockwise. Initial clockwise movement of the shaft 19 brings the parts into position shown in Fig. 3. As there shown the pin 17 operates through the agency of the link 30 to rock the catch 23 anti-clockwise about its pivot 22 against the action of spring 24, thus removing the obstruction to disengagement of the cable 33 from the hook 14. At the same time link 15 serves to rotate the hook 14 anti-clockwise about its pivot pin 13.

If the flying boat is tending to drift in an aft direction in relation to the cable the latter will now be free to disengage from the hook.

Further clockwise rotation of the release shaft 19 brings the parts into the position shown in Fig. 4. The hook 14 is now sufficiently retracted to free the cable and permit of rearward movement thereof in relation to the flying boat. If therefore the flying boat is tending to drift forwardly in relation to the cable, the latter is free to pass under the keel and rise to the surface behind the aircraft. It will be noted that in this case the pull of the cable in an aft direction assists the casting-off process.

Should the aircraft be entirely stationary on the water during the casting-off process, the arm 26 operates, when the parts have arrived at the position shown in Fig. 5, to eject the cable 33 and force it beneath the keel.

Finally, completion of the clockwise rotation of the shaft 19 brings the parts into the position shown in Fig. 6 in which the mooring gear is fully retracted and the plate 25 closes the aperture 10 in the keel.

Reverse rotation of the shaft 19 will return the parts to the position shown in Fig. 1 in which the mooring hook 14 is extended and held in the operative position ready to receive the cable.

What I claim as my invention and desire to secure by Letters Patent is:

1. In a flying boat, the combination with a forwardly facing mooring hook pivotally mounted on the boat for movement about a transverse axis and normally projecting beneath the keel thereof, said hook serving to engage a mooring cable stretched under the water, of a spring loaded catch fitted to the hook and adapted to be pushed aside by the cable to allow the same to enter the hook and thereafter to be returned by its spring to prevent disengagement of the cable from the hook, a pivoted operating lever, manually operable means for rotating said lever about its pivot to disengage said cable from the hook, a first link coupling said lever to said catch and serving, on initial rotation of said lever, to displace said catch into position to allow the cable to leave the hook, said first link being coupled to said lever by a connection arranged to impart positive movement to said first link when said lever is rotated, but permitting said first link to move in relation to said lever when the catch is pushed aside by a cable entering the hook, and a second link coupling said lever to hook and serving, on initial rotation of the lever, to effect upward and rearward pivotal movement of the hook in relation to the keel into a position permitting the cable to become disengaged from the hook both by forward and by aft movement of the boat in relation to the cable.

2. In a flying boat, a combination as claimed in claim 1, wherein said second link and said lever are formed with abutments which coact to provide

a rigid support for the hook when in its normal projected position, said abutments becoming separated on rotation of said lever.

3. In a flying boat, a combination as claimed in claim 1, comprising a recess in the hull into which the hook is retractable by said second link on continued rotation of the lever beyond the cable release positions and a plate carried by the hook and normally housed within the recess, said plate being positioned on the hook so that, on pivotal movement of the hook to retract it into the recess it will form a closure for the lower end of said recess, said plate operating, if necessary, to force the cable rearwardly beneath the keel as it moves to position to close said recess.

4. A mooring gear attachable to the keel of a boat and comprising a casing to fit within a recess in the keel, a mooring hook supported by the casing and movable in relation thereto between a projected position in which it may engage a submerged mooring cable, and a retracted position in which it may cast off the cable by forward or aft movement of the boat in relation to the cable, a manually operable member for moving the hook at will to its projected or retracted position, a catch fitted to the hook and normally positioned to trap a cable engaged by the hook, said catch being free to move aside when contacted by a cable to permit the cable to enter the hook, and means actuated by said manually operable member, on movement thereof to move the hook from its projected position to the retracted position, to displace said catch from trapping position into a position allowing an engaged cable to leave the hook.

5. In combination with the hull of a flying boat, a mooring hook fitted to said hull near the bow and movable in relation to said hull between a projected position in which it may engage a submerged mooring cable and a withdrawn position in which it may cast off an engaged mooring cable, means operable from within the boat for moving said hook between said two positions, a catch mounted on the hook and biased so as normally to prevent disengagement of the cable from the hook, said catch being movable, when contacted by a submerged cable, into a position permitting the cable to enter the hook and thereafter returning to normal position, and means connecting the catch and said moving means for displacing the catch, on operation of said moving means to move the hook from projected to withdrawn position, into a position permitting disengagement of the cable from the hook.

6. In a flying boat, the combination with a forwardly facing mooring hook pivotally mounted on the boat, means for normally retaining the hook in a projected position in which it projects below the keel of the boat to engage a submerged mooring cable, means operable from within the boat for moving the hook rearwardly and upwardly about its pivot into positions allowing an engaged cable to leave the hook both by forward and by aft movement of the boat in relation to the cable, a spring loaded catch mounted on the hook and adapted to be moved aside by an entering cable and thereafter to return to position to trap the cable in the hook, and means operating, on operation of said moving means to move the hook from projected position, to displace the catch from trapping position to allow the cable to leave the hook on continued rearward and upward pivotal movement thereof.

7. In a flying boat, the combination with a forwardly facing mooring hook pivotally mount-

ed on the boat, means for normally retaining the hook in a projected position in which it projects below the keel of the boat to engage a submerged mooring cable, means operable from within the boat for moving the hook rearwardly and upwardly about its pivot to retract it into a recess in the boat, a spring loaded catch mounted on the hook and adapted to be moved aside by an entering cable and thereafter to return to position to trap the cable in the hook, and means operating, on operation of said moving means to retract the hook to displace the catch from trapping position

to allow the cable to leave the hook on continued rearward and upward pivotal movement thereof.
